Primary Examiner — Patricia Palasik(74) *Attorney, Agent, or Firm* — Hahn, Loeser & Parks, LLP(57) **CLAIM**

The ornamental design for a packing bead ring for a wire coil, as shown and described.

DESCRIPTION

FIG. 1 is a perspective view of a packing bead ring for a wire coil showing our new design;

FIG. 2 is a top view thereof;

FIG. 3 is a side view thereof with the front, rear, left, and right views all being mirror images;

FIG. 4 is a sectional view taken along line 4-4 in FIG. 2; and, FIG. 5 is an enlarged view of the area indicated in FIG. 1 to show further detail of the packing bead ring for a wire coil design.

The broken lines shown are environmental only and form no part of the claimed design.
